BACKBOARD FOR AN AMUSEMENT DEVICE OR THE LIKE

Omey M. Monkres, Long Beach, Calif., assignor of one-half to Arthur P. Smith, Long Beach, Calif.

Application June 26, 1948, Serial No. 147,218

Term of patent 3½ years

(Cl. D34—5)

To all whom it may concern:

Be it known that I, Omey M. Monkres, a citizen of the United States of America and residing in Long Beach, in the county of Los Angeles and State of California, have invented a new, original, and ornamental Design for a Backboard for an Amusement Device or the like, of which the following is a specification, reference being had to the accompanying drawings, forming a part thereof.

In the accompanying drawings the single figure is a perspective view of a backboard for an amusement device or the like, showing my new design;

I claim:

The ornamental design for a backboard for an amusement device or the like, substantially as shown.

OMEY M. MONKRES.
